(No Model.)

D. D. FUNK.

CULTIVATOR.

No. 352,533.

Patented Nov. 16, 1886.

UNITED STATES PATENT OFFICE.

DANIEL D. FUNK, OF FREMONT, OHIO.

CULTIVATOR.

SPECIFICATION forming part of Letters Patent No. 352,533, dated November 16, 1886.

Application filed August 24, 1886. Serial No. 211,755. (No model.)

To all whom it may concern:

Be it known that I, DANIEL D. FUNK, a citizen of the United States, residing at Fremont, in the county of Sandusky and State of Ohio, have invented a new and useful Improvement in Cultivators, of which the following is a specification.

My invention relates to an improvement in sulky-cultivators; and it consists in the peculiar construction and combination of devices, that will be more fully set forth hereinafter, and particularly pointed out in the claims.

In the drawings, Figure 1 is a side elevation of a sulky-cultivator embodying my improvements. Fig. 3 is a top plan view of the same. Fig. 2 is a vertical longitudinal sectional view taken on the line $x-x$ of Fig. 2.

A represents the axle, which is bent from a metallic bar or pipe, and is formed with an arch, B, thereby forming a raised central horizontal portion, C, vertical bars D, and horizontal spindles E at the lower ends of the said vertical bars. On the said spindles are mounted supporting-wheels F.

G represents a yoke, which is bent substantially in the shape of the letter U, and the rear ends of the arms of the said yoke are connected to the raised horizontal central portion of the axle by means of T-couplings H.

I represents brace-rods, which extend from the spindles of the axle to the front end of the yoke, and are connected to the said spindles and to the yoke, as shown. This yoke, arched axle, and brace-rods constitute the frame of the machine, and may be made either of gas or water pipes of suitable size or of iron rods.

K represents the draft pole or tongue, the rear end of which is bifurcated, and is attached to the central portion of the yoke and to the central portion of the arched axle by means of clip-bolts L.

M represents a transverse draft-bar, provided at its extremities with ears N, having sleeves N', that slide upon the arms of the yoke G. Set-screws O work in threaded openings in the said sleeves and bind against the arms of the yoke, and thus clamp the draft-bar to the arms of the yoke at any desired adjustment.

P represents a pair of sliding collars, which

are placed on the draft-bar, and are provided with set-screws P', by means of which they may be clamped to the draft-bar at any desired lateral adjustment thereon. Sliding 55 hangers R are hinged on the draft-bar, being provided with hinged ears which extend on each side of one of the collars P, and from the front sides of the said hangers, near the lower ends thereof, project blocks R'.

S represents draft-arms, which are curved rearwardly, as shown, and have their upper reduced ends swiveled in vertical openings, which are made in the blocks R' of the hangers. The said draft-arms have their lower 65 ends bifurcated, and between the bifurcated ends of the draft-arms are pivoted the front ends of the cultivator-beams T. The said cultivator-beams have their front ends curved upwardly to correspond with the draft-arms S, and the extreme front upper ends of the cultivator-beams are flattened to form heads T', which are provided with a number of transverse openings T''. Transverse openings S' are made near the upper ends of the draft-arms, and 70 pins V are adapted to extend through the said openings S' and through one of the openings T'' of each of the cultivator-beams, so as to lock the latter rigidly to the draft-arms at any desired adjustment with respect to the latter. 80 The cultivator-beams are provided with cultivator-shovels T³, of suitable construction.

When the pins V are removed, the rear ends of the cultivator-beams may be raised so as to lift the cultivating-shovels from the ground, 85 and in order to elevate the rear ends of the cultivator-beams I provide hand-levers U, which are pivoted on the rear bifurcated ends of the tongue or pole, and are connected to the cultivator-beams by means of rods U'.

W represents an evener or double-tree, which is bolted on the underside of the tongue in rear of the draft-bar, and the said evener or double-tree is provided with pendent draft-hangers X, having each a series of openings, 95 X'. When the cultivator-beams are lowered to the desired distance so as to cause the cultivating-shovels to work to the requisite depth in the ground, a pin or bolt, X'', is passed through an opening which is made in each of the cultivator-beams and through one of the openings X' in each hanger-rod. Single-trees

Y are attached to the hanger-rod at the required vertical adjustment, and thus the draft is attached directly to the cultivator-beams.

A seat for the driver is supported on the 5 rear end of a bar, L, the front bifurcated end of which is attached to the rear bifurcated end of the tongue by a rod or bolt that extends transversely through the said bar and tongue. The seat-bar rests upon the axle.

10 To the beams of the cultivators are attached stirrups *a*, each of which has a series of rests or rungs for the feet. The driver seats himself in the seat and places his feet in the stirrups, and then can very readily manage the 15 team and the plows. By providing the stirrups with a number of foot-rests or rungs the driver can dispose his feet very comfortably on them.

Having thus described my invention, I 20 claim—

1. In a sulky-cultivator, the combination of the arched axle, the yoke having the rear ends of its arms attached to the axle, the transverse draft-bar clamped to the arms of the said 25 yoke and adjustable longitudinally thereon, and the cultivator-beams connected to the said draft-bar, substantially as described.

2. The combination, in a sulky-cultivator, 30 of the draft-bar, the hangers R, laterally adjustable thereon, the draft-arms S, connected

to the said hangers, and the cultivator-beams connected to the draft-arm, substantially as described.

3. The combination of the sulky-frame having the draft-bar with the hangers R, hinged to the said draft-bar, the draft-arms attached to the said hangers, the cultivator-beams attached to the draft-arms, and the evener or double-tree having the depending hanger-rods X connected to the cultivator-beams, and the 40 single-trees attached to the said hanger-rods, whereby the draft is applied directly to the cultivator-beams, substantially as described.

4. The combination, in a sulky-cultivator, of the draft-bar, the hangers R, hinged thereto, 45 the draft-arms swiveled to the said hangers and having the transverse openings S', the cultivator-beams pivoted to the draft-arms and having the openings P² at their upper ends, adapted to coincide with the openings S', 50 and the bolts or pins V, adapted to enter the said openings S' and P², substantially as described.

In testimony that I claim the foregoing as my own I have hereto affixed my signature in 55 presence of two witnesses.

DANIEL D. FUNK.
